ALARM SWITCH DEVICE

Frederick Henry Townsend and Harvey Sydney Hall, Cambridge, England, assignors to Cathodeon Limited, Cambridge, England, a British company

Application December 31, 1951, Serial No. 264,302
In Great Britain October 25, 1951

11 Claims. (Cl. 200—52)

1

The present invention relates to alarm switch devices for completing electrical circuits in the event of emergencies, more particularly to such devices that comprise an outer casing of frangible material having an elongated tubular form closed at one end, a rod electrode enclosed within said outer casing and extending substantially coaxially of the casing and for substantially the entire length thereof, and a coiled electrode surrounding and spaced from the rod, the two electrodes being adapted to be connected to a suitable electric circuit.

More specifically it is the object of the invention to provide a switch device of this kind which is positive in its operation and more efficient in use.

According to the invention there is provided an alarm switch device of the kind referred to in which the end of the rod electrode at the closed end of the outer casing is located in a block of insulating material to prevent lateral movement of the rod in the inoperative state of the switch.

Preferably there is provided a second operating spring associated with a contact member electrically connected to the coiled electrode and surrounding and spaced from the rod, together with a co-operating contact member on the rod, the spring being held under load and the arrangement being such that in the event of fracture of the outer casing and consequent removal of the lower half thereof, the loading of the spring is removed to bring about contact between the two contact members.

The detector device may be adapted to co-operate with a separate socket device mounted on a suitable surface or it may be incorporated integrally with a mounting containing appropriate terminals.

In a preferred embodiment the coiled electrode is in the form of a spring held under compression within the outer casing and the second operating spring is mounted in end-to-end relationship with it also under compression so that in the event of fracture of the outer casing by sideways impact, completely removing the lower part of the casing, the coiled electrode moves to remove the compressive loading of the second operating spring whereby the latter expands longitudinally to allow the contact member with which it is associated to contact the co-operating member on the rod electrode.

In order that the invention may be more clearly understood, reference will now be made to the accompanying drawings which show certain specific embodiments thereof by way of non-limiting example and in which

2

Fig. 1 shows a section through one embodiment of switch used in conjunction with a separable mounting socket.

Fig. 2 shows a plan view along the line 2—2 of Fig. 1.

Fig. 3 shows a plan view along the line 3—3 of Fig. 1.

Fig. 4 shows a section through a second embodiment showing the incorporation of the device integrally with a mounting containing appropriate terminals.

Fig. 5 shows a plan view of Fig. 4.

Referring to the drawings, 1 represents the outer casing of the device which is preferably made from glass. The casing is of tubular elongated form closed at the lower end 2. At the upper end is provided a metal flange 3 which acts as a seating for centralising metal mounting 4 for the metal rod electrode 5. The rod 5 is mounted in the mounting 4 by means of a glass bead 7 which is sealed to the mounting 4 and to the rod.

The other end of the rod 5 is held and located by the member 8 of the insulating material.

Surrounding the rod 5 is a coiled electrode 9 in the form of a spring which bears at one end on a metal cup 10 centralised on the member 8 by tags 11. The base of the cup is apertured at 12 to allow the rod 5 to pass into the aperture 13 in the member 8. The aperture 12 is sufficiently large to clear the rod 5. At the other end of the spring electrode 9 is a further cup 14 having shoulders 15 preventing inward movement of the electrode 9. The cup 14 also has an aperture 16 sufficiently large to clear the rod 5.

The cup 14 is accommodated within another cup 17 having flanges 18 preventing outward movement of electrode 9 and the cup 17 also forms a mounting for a second operating spring 19 which is mounted between the shoulder 20 on the cup 17 and the underside of mounting 4.

The cup 17 is provided with a constricted shoulder 21 which acts as a contact member for co-operation with contact 22 secured to the rod 5, as will be explained later.

The rod 5 is also provided with a further contact 23 near its other end as shown.

The mounting 4 is surrounded by a threaded portion 24 for co-operation with the socket shown in Figs. 2 and 3, underneath which is positioned a metal washer 6.

In assembling the device, the parts 3, 4, 6 and 24 are connected together, e. g. by soldering and the springs 9 and 19 are of such normal length that they must be compressed for insertion into

the casing 1. The metal flange 3 is hermetically sealed on to the casing 1 whereby the ingress of moisture into the device is prevented so as to avoid risk of corrosion of the metal parts. A suitable termination for the rod 5 is shown at 25.

A suitable socket for the device of Fig. 1 is shown in Figs. 2 and 3. The socket comprises a body 26 of suitable material such as metal having a mounting flange 27 for attachment to a suitable surface, e. g. by screws passing through apertures 28 therein.

An insulated bush 29 lines the body 26 and is prevented from turning therein by a suitable key 30 situated at the base thereof fitting closely in an aperture 31 in the body. The bush 29 locates a spring 32 which itself is prevented from turning in the bush by forming one end with a radially-projecting portion 33 fitting in a slot 34 cut in the bush 29 from its top to the key 30.

The spring 32 is adapted to receive the switch device. The pitch of the spring is less than the pitch of the threads on the threaded portion 24, so that when the switch is screwed into the socket the spring is placed under tension thereby ensuring good connection between the parts 25 and 42. At the same time it forms a convenient means of reducing the transmission to the switch of any vibrations of the surface on which the device is mounted. The washer 6 causes the end of the spring 32 to jam in the top of the thread in member 24 before the radially-projecting portion 33 comes up against the bottom of the slot 34 in the bush 29.

The upper end of spring 32 has a projecting portion 35 soldered to a terminal member 36 located in a recess 37 in a terminal block 38 of insulating material. The latter has a further recess 39 accommodating a second terminal 40 soldered to lead 41 which goes to a centre contact stud 42 located in a recess 43 in the underside of block 38. The two terminals 36 and 40 are soldered to 35 and 41 respectively thereby securing them in position and providing electrical connection. Screws 44 and 45 are provided in terminals 36 and 40 respectively to clamp external circuit leads.

The block 38 is secured to the body 26 by screws 46, 47 (see Fig. 4). A rubber washer 48 separates the block 38 and the body 26.

Channels 49 and 50 are made in the block 38 for electrical leads to the terminals 36 and 40. These channels 49, 50 are provided with rubber seals 51, 52 located in suitable recesses, through which external circuit leads are connected to the terminals. This forms a convenient means of waterproofing the lead entry.

The block 38 also has screw holes 53 for affixing a cover plate 54. A rubber washer 55 is interposed between the cover plate 54 and the block 38.

The switch device is screwed into the spring 32 and a cover 56 is engaged over it. The cover is of metal and has threads 57 to engage threads 58 on the outside of body 26. A rubber gasket 59 serves to cushion and support the switch and provide waterproofing.

There is thus electrical continuity between terminal 36, spring 32, threads 24, mounting 4, spring 19, cup 17, cup 14, spring electrode 9 and cup 10, and between terminal 40, contact stud 42, terminal 25, rod 5 and contacts 22 and 23.

To operate the switch it is only necessary to strike a blow on the casing 1 from any direction. If the blow is sideways, acting to remove completely the lower part of the glass casing, there will be no support for the compressed coil spring

electrode 9 which will thus expand and remove its support from the second operating spring 19. The latter will move longitudinally until contact shoulder 21 strikes contact member 22 on the rod 5 establishing electrical contact between terminals 36 and 40 by the electrically conducting paths set out above. Thus, if the terminals 36 and 40 be connected in a suitable alarm circuit, breaking of the casing 1 will institute an alarm.

If the blow on the casing 1 be end-on, crushing the glass in a longitudinal compressing action, the spring 9 will be further compressed until the cup 19 strikes the contact 23 thereby establishing electrical continuity over the paths provided.

If the blow be a sideways one, it is feasible that no longitudinal movement of the contacts is possible but the sideways pressure will cause contact to be made between the coiled spring electrode 9 and the rod electrode 5.

Figs. 4 and 5 show an embodiment of the switch incorporating its own mounting and terminals as an integral structure.

All the operating parts are the same as the embodiment of Fig. 1 and have the same reference numerals. The closure devices for the upper end of the case are, however, different to provide for the integral mounting.

Surrounding the metal mounting 4 is an annular closure member 60 having a radially extending flange 61. This flange provides a mounting bracket for the device and to this end is provided with apertures 62 for the passage of screws or the like. The member 60 is soldered to the mounting 4.

The rod 5 is connected by a lead 64 to an external terminal 65. The upper portion of the device as now constituted is placed in a suitable mould that grips the edges of the flange 61 and a synthetic resin material is poured in which, when set, produces a block 66 of insulating material that seals off the upper portion completely, suitably embedding the terminal 65. The mould has a suitable plug to form a recess 67 for connection of a suitable lead to the terminal 65 which is threaded at 68 for a fixing screw.

In use the flange 61 acts as one terminal so that the device can be secured to a suitable metal fixing to which one lead of the alarm circuit is made, the other lead being taken to terminal 65.

The operation of the device of Figs. 4 and 5 is precisely the same as that of Fig. 1.

The invention thus provides an extremely simple alarm switch operable by breaking the casing 1. It may, therefore, be used as a crash-detector switch for vehicles, particularly aircraft, when it could be secured to the craft to depend downwards immediately behind the outer skin or even externally from its body to effect actuation of an alarm circuit on impingement. The alarm circuit may comprise a simple warning signal device such as a lamp or buzzer or, preferably for this purpose, it may comprise a fire-fighting installation whereby a crash landing will automatically actuate fire-prevention or fire-fighting devices, such as sprays for fire-extinguishing compounds.

Alternatively, of course, the device may merely be mounted in a wall and connected to suitable warning circuits so that it may be used as an emergency signal device.

In order to be able to test the installation, the rod 5 may have a connection such as that shown at 69 in Fig. 4. The connection 69 is sealed into and through the wall of the cover 1 to project externally at 70. If then a connection be made externally of the device between point 70 and the

flange 61, the circuit in which the device is connected will be completed whereby continuity of the circuit and effectiveness thereof may be rapidly tested.

We claim:

1. An alarm switch device for completing electrical circuits in the event of emergencies comprising an outer casing of frangible material having an elongated tubular form closed at one end, a rod electrode enclosed within said outer casing and extending substantially coaxially of the casing and for substantially the entire length thereof, a coiled electrode surrounding and spaced from said rod electrode, a block of insulating material supported by the closed end of said frangible envelope, means for locating said rod electrode in said block of insulating material out of contact with said coiled electrode, an external contact on said casing, means for connecting said external contact to said coiled electrode, said rod electrode being sealed into but projecting out of said casing, and sealing means for hermetically sealing said casing against the ingress of fluids and gases.

2. An alarm switch device as claimed in claim 1, in which the external contact is a screw thread and the projecting rod electrode is arranged coaxially with it.

3. An alarm switch device comprising a socket, two terminal contacts in said socket, an external screw thread on said socket, a demountable switch removably engaging in said socket and comprising an outer casing of frangible material having an elongated tubular form closed at one end, a rod electrode enclosed within said outer casing and extending substantially coaxially of the casing and for substantially the entire length thereof, a coiled electrode surrounding and spaced from said rod, a block of insulating material supported within said frangible casing at the closed end thereof, means for locating said rod electrode in said insulating block out of contact with said coiled electrode, contact means externally of said casing connected respectively to said two electrodes, said contact terminals in said socket being positioned for contact with said two external contacts on said switch device casing when said switch device is mounted within said socket, a closure device comprising a cap centrally apertured and having an internal screw thread so located and arranged that said closure device may be slipped over said casing protruding from said socket to allow the threads internally arranged on said closure device to engage over the threads externally arranged on said socket, and a flexible gasket arranged between the end of said socket and the interior of said closure device to cushion said demountable switch within said socket and closure device assembly.

4. An alarm switch device comprising a socket, two terminal contacts in said socket, a demountable switch removably engaging in said socket and comprising an outer casing of frangible material having an elongated tubular form closed at one end, a rod electrode enclosed within said outer casing and extending substantially coaxially of the casing and for substantially the entire length thereof, a coiled electrode surrounding and spaced from said rod, a block of insulating material supported within said frangible casing at the closed end thereof, means for locating said rod electrode in said insulating block, and contact means externally of said casing connected respectively to said two electrodes, said contact terminals in said socket being positioned for contact

with said two external contacts on said switch device casing when said switch device is mounted within said socket.

5. An alarm switch device as claimed in claim 4, comprising a coil spring in said socket, locating means in said socket for locating said spring therewithin, and means connecting said coil spring to one of said contact terminals in said socket.

10 6. An alarm switch device as claimed in claim 4, comprising electrically-conducting external screw thread means on said frangible casing adapted to engage within the convolutions of said coil spring in said socket, said screw thread on 15 said frangible casing comprising an external terminal connected to one of said electrodes within said casing.

7. An alarm switch device for completing electrical circuits in the event of emergencies comprising an outer casing of frangible material having an elongated tubular form closed at one end, a rod electrode enclosed within said outer casing and extending substantially coaxially of the casing and for substantially the entire length thereof, a coiled electrode surrounding and spaced from said rod electrode, a block of insulating material supported by the closed end of said frangible envelope, means for locating said rod electrode in said block of insulating material out of contact with said coiled electrode, a metal closure cap for the open end of said frangible casing, means for connecting said cap to said coiled electrode, a mounting flange associated with said cap, said rod electrode being sealed into but projecting out of said casing out of contact with said cap, a terminal for external connection connected to said projecting rod electrode, and a block of insulating material moulded around said cap and terminal and over said

25 flange but allowing a portion of said flange to protrude for mounting purposes and leaving exposed a portion of said terminal for external connection.

8. An alarm switch device as claimed in claim 7, and comprising further a second operating spring, a first contact member electrically connected to said coiled electrode within said casing, said operating spring being associated with said contact member and surrounding and spaced from said rod electrode, a second cooperating contact member on said rod located normally out of contact with said first contact member and means for normally holding said second operating spring under load, whereby in the event of fracture of the frangible casing the loading of said operating spring is removed to bring about contact between said two contact members.

9. An alarm switch device for completing electrical circuits in the event of emergencies comprising an outer casing of frangible material having an elongated tubular form closed at one end, a rod electrode enclosed within said outer casing and extending substantially coaxially of the casing and for substantially the entire length thereof, a coiled electrode surrounding and spaced from said rod electrode, means for locating said rod electrode out of contact with said coiled electrode, an operating spring, a first contact member electrically connected to said coiled electrode within said casing, said operating spring being associated with said first contact member and surrounding and spaced from said rod electrode, a second cooperating contact member on said rod located normally out of contact with said first contact member, and means for nor-

60 10 75

normally holding said second operating spring under load whereby in the event of fracture of the frangible casing the loading of said operating spring is removed to bring about contact between said first and said second contact members, an external contact on said casing, means for connecting said external contact to said coiled electrode, said rod electrode being sealed into but projecting out of said casing, and sealing means for hermetically sealing said casing against the ingress of fluids.

10. An alarm switch device comprising a socket, two terminal contacts in said socket, an external screw thread on said socket, a demountable switch removably engaging in said socket and comprising an outer casing of frangible material having an elongated tubular form closed at one end, a rod electrode enclosed within said outer casing and extending substantially coaxially of the casing and for substantially the entire length thereof, a coiled electrode surrounding and spaced from said rod, a block of insulating material supported within said frangible casing at the closed end thereof, means for locating said rod electrode in said insulating block out of contact with said coiled electrode, an operating spring, a first contact member electrically connected to said coiled electrode within said casing, said operating spring being associated with said first contact member and surrounding and spaced from said rod electrode, a second cooperating contact member on said rod located normally out of contact with said first contact member, and means for normally holding said second operating spring under load whereby in the event of fracture of the frangible casing the loading of said operating spring is removed to bring about contact between said first and said second contact members, contact means externally of said casing connected respectively to said two electrodes, said contact terminals in said socket being positioned for contact with said two external contacts on said switch device casing when said switch device is mounted within said socket, a closure device comprising a cap centrally apertured and having an internal screw thread so located and arranged that said closure device may be slipped over said casing protruding from

5 said socket to allow the threads internally arranged on said closure device to engage over the threads externally arranged on said socket, and a flexible gasket arranged between the end of said socket and the interior of said closure device to cushion said demountable switch within said socket and closure device assembly.

11. An alarm switch device comprising a socket, two terminal contacts in said socket, a demountable switch removably engaging in said socket and comprising an outer casing of frangible material having an elongated tubular form closed at one end, a rod electrode enclosed within 10 said outer casing and extending substantially coaxially of the casing and for substantially the entire length thereof, a coiled electrode surrounding and spaced from said rod, a block of insulating material supported within said frangible casing at the closed end thereof, means for locating said rod electrode in said insulating block, an operating spring, a first contact member electrically connected to said coiled electrode within said casing, said operating spring being associated with said first contact member and surrounding and spaced from said rod electrode, a second cooperating contact member on said rod located normally out of contact with said first contact member, and means for normally holding 15 said second operating spring under load whereby in the event of fracture of the frangible casing the loading of said operating spring is removed to bring about contact between said first and said second contact members, and contact means externally of said casing connected respectively to said two electrodes, said contact terminals in said socket being positioned for contact with said two external contacts on said switch device casing when said switch device is mounted within said socket.
